(57) **CLAIM**

The ornamental design of a modular person transport chair, as shown and described.

DESCRIPTION

FIG. 1 is a perspective view of the modular person transport chair of our new design;

FIG. 2 is a top plan view thereof;

FIG. 3 is a front elevational view thereof;

FIG. 4 is a rear elevational view thereof;

FIG. 5 is a side elevational view of the right side thereof;

FIG. 6 is a side elevational view of the left side thereof;

FIG. 7 is a bottom plan view thereof;

FIG. 8 is an exploded perspective view of the chair of FIG. 1 without the seat and back rest;

FIG. 9 is a perspective view of a modification of the modular person transport chair of my new design;

FIG. 10 is a top plan view of FIG. 9;

FIG. 11 is a front elevational view of FIG. 9;

FIG. 12 is a rear elevational view of FIG. 9;

FIG. 13 is a side elevational view of the right side of FIG. 9;

FIG. 14 is a side elevational view of the left side of FIG. 9;

FIG. 15 is a bottom plan view of FIG. 9; and,

FIG. 16 is an exploded perspective view of the chair of FIG. 9 without the seat and back rest.
